UNITED STATES PATENT OFFICE.

WILLIAM W. TAYLOR, OF MONTCLAIR, NEW JERSEY.

DESIGN FOR A PORTABLE STRUCTURE.

44,738.

Specification for Design.

Patented Oct. 14, 1913.

Application filed May 9, 1913. Serial No. 766,609. Term of patent 14 years.

To all whom it may concern:

Be it known that I, WILLIAM W. TAYLOR, a citizen of the United States, residing at Montclair, in the county of Essex and State of New Jersey, have invented a new, original, and ornamental Design for a Portable Structure, of which the following is a specification, reference being had to the accompanying drawing, forming part thereof.

The figure is a perspective view of a portable structure showing my new design.

I claim:

The ornamental design for a portable structure, as shown.

WILLIAM W. TAYLOR.

Witnesses:

J. L. McAULIFF,

PHILIP D. ROLLHAUS.
